MOVEMENT-PRODUCING DEVICE

Lincoln K. Davis, Brockton, Mass.

Application April 6, 1935, Serial No. 15,033
Renewed May 4, 1939

23 Claims. (Cl. 200—137)

This invention relates to movement-producing devices.

More particularly, the invention relates to movement-producing devices, such as thermostats, hygostats and the like, wherein a change in length of a control element, induced by a predetermined change in the physical condition of a substance or medium surrounding the control element, is employed to effect movement of an operator controlling a connected device, such as an electric switch, a valve, an indicator, or the like.

In such devices, extreme sensitivity often is required, in which event a very slight change in length of the control element must be caused to produce a much greater movement of the operator in order that the operator will be moved sufficiently to actuate the associated device.

It also often is a desideratum in such devices that the control element be quickly responsive to change its length in accordance with a change in the physical condition of the surrounding substance or medium, in order that the operator will be moved promptly to effect the operation of the associated device within a short interval after the change in the physical condition of the substance.

In certain instances, it is desirable that the movement of the operator be accomplished by an accelerated movement, or "snap-action", so that an acceleration may be given to the associated device, or that a positive indication of the operation will be given, or that an electric switch will be opened or closed quickly, and so forth. In order to accomplish this, the movement producing device must have a "snap-action" mechanism therein, or must produce this effect inherently by its construction.

The present invention relates to a device wherein an element, such as a plate, frame, dish or the like, is formed with a rigid or confined portion and a flexible or otherwise movable portion, and a second element is attached to the flexible or otherwise movable portion, and is responsive to change its length in accordance with a change in the nature of the surrounding medium to effect a movement of the first-named element, or a portion thereof.

The invention also concerns a device wherein the element, which changes its length, is of such form and size and is so attached to the other element that the device is quickly sensitive to changes in the substance or medium controlling its operation.

Another feature of the invention is the provision of a device of the above-described type,

wherein the movable element is so formed or supported as to have a position of instability, and which is movable by the other element from a position of stability into the position of instability from whence it moves, due to its own internal stresses, to a second position of stability, whereby to provide a "snap-action."

Other and special objects of the invention will appear from the appended description taken in connection with the drawings wherein like reference characters denote like parts.

Although the invention is herein disclosed with reference to several specific embodiments in order to clearly illustrate the same, it is not limited thereto, and the appended claims are to be read as broadly as is consistent with the prior art.

In the drawings accompanying and forming part of this specification, certain specific disclosure of the invention is made for purposes of explanation, but it will be understood that the details may be modified in various respects without departure from the broad aspect of the invention.

Fig. 1 is an isometric view showing a thermostat constructed according to the present invention.

Fig. 2 is an enlarged fragmentary view of a cross-section taken along line 2—2 of Fig. 1.

Fig. 3 is a diagram illustrating certain principles of the invention.

Fig. 4 is another diagram illustrating further principles.

Fig. 5 is a top plan view showing a thermostat constructed according to the invention and adapted for use as an electric switch.

Fig. 6 is a side elevational view showing the device of Fig. 5.

Figs. 7, 8 and 9 are isometric views showing three modifications of the thermostat respectively, and

Figs. 10, 11 and 12 are enlarged fragmentary views showing respectively modifications of the method of attaching the wires to the frame, and

Fig. 13 is a diagrammatic view representing a section taken along a diagonal of a modified form of thermostat.

Referring now particularly to Fig. 1 of the drawings, a thermostat 1 comprises a frame 2 formed from an initially planar rectangular sheet (not shown) of flexible metal, and having stiffening beads 3 extending along the marginal portion 50 of each side. The beads are discontinuous at the corner portions 4 of the frame, thus permitting flexure of the frame along its diagonals.

Portions of the sheet from which the frame is formed are cut out to provide a cruciform strap 55

5 integral with the frame 2, having its arms 6 integrally connected with the mid-portions of the sides of the frame 2 respectively, and its central portion 7 offset to place the arms 6 under a tensile stress acting to draw the mid-points of opposite sides of the frame 2 closer together, for a purpose which will hereinafter be pointed out. Each of the arms 6 of the strap 5 is formed with a reduced portion 8 closely adjacent the juncture 10 of the arm 6 and the side of the frame 2 to increase the flexibility of the arm 6 relative to the frame 2.

Extending along a diagonal of the frame 2 is wire 10a, which is secured at its ends to one face 15 of the frame at opposite corner portions. The wire 10a is attached to the frame 1 by suitable means, for example, soldering or brazing 12a, and is under tension as will later be explained. A second wire 11a, having a lesser unit length 20 thermal expansibility than that of the wire 10a, is attached to the other face of the frame at the corner portions in a manner analogous to the first wire 10a, by soldering or welding 13a. A second pair of wires 10b and 11b, similar to the 25 wires 10a and 11a, are connected between the other two corner portions for a purpose which will appear hereinafter.

If an initially planar sheet or frame of resilient material, having a discontinuously stiffened 30 peripheral portion providing two pairs of oppositely disposed stiffened sides and two pairs of flexible portions intermediate the stiffened sides, is stressed to force the oppositely disposed stiffened sides close to one another, the sheet or 35 frame will not remain planar but will warp with opposite curvature along intersecting lines extending between opposite flexible portions, to lie in the surface of an hyperbolic paraboloid.

This will be seen from an inspection of the diagram (Fig. 3), wherein the frame 2 is represented diagrammatically as a surface. If opposing forces are applied to the midpoints W and Y of opposite sides respectively of the frame 2 (or at the points X and Z, or at points W, X, Y and Z), 40 the frame will be warped into either the position A'B'C'D' or A''B''C''D'', and will lie in the surface of an hyperbolic paraboloid. In either of these positions the frame will be curved oppositely along its diagonals which become parabolas, for 45 example, in the position A'B'C'D', the frame is curved in one direction about A'C' and in the opposite sense about B'D'. As viewed in the diagram, the frame is concave along B'D', and convex along A'C'.

50 This warping results from the fact that when the sides are forced toward one another, unrelieved stresses are set up in the frame due to the rigidity of the side portions, and the frame is in a position of instability. The unrelieved stresses 55 force the frame to assume the warped position A'B'C'D' or A''B''C''D''. If the frame is in the position A'B'C'D', for example, and a force is applied which is slightly greater than necessary to return the frame to the initial position ABCD, unrelieved stresses are set up which prevent the 60 frame from remaining in this position, and the frame is moved rapidly through the position of instability ABCD to the other position of stability A''B''C''D''.

70 This abrupt change of curvature as the frame passes through the position of instability or "dead center" position permits the unrelieved stress to come into play and move the frame from the position of instability to the second position

of stability without the aid of any external force. Thus a "snap-action" of the frame is provided.

If the thermostat 1 (Fig. 1), shown in its position of instability, is left free to assume a position of stability, the tension on the arms 6 draws the 5 mid-points of the sides closer together, and the frame 2 is warped to a position wherein it is curved oppositely along the diagonals. The wires 10a and 11a are under the tension initially applied when they are attached to the frame 2.

Assuming the thermostat 1 to be in a position corresponding to the position A'B'C'D' of the diagram, an increase in the temperature of the air surrounding the thermostat causes the wires 10a and 11a to increase their lengths; the frame 15 also expands to increase the distance between the points of attachment of the wires 10a, 11a. Since the wire 10a has a greater unit length thermal 20 expansibility, it will elongate more than the wire 11a, and thus the stress which the wire 10a exerts 25 on the frame to bow it along the diagonal B'D' becomes less than the stress exerted by the wire 11a, tending to bow the frame in the opposite sense along the diagonal.

The wires 10a and 11a are displaced a distance 25 k from a median surface (indicated by MN in Fig. 2) passing through the frame and parallel to its faces, and exert opposite moments of force upon the frame tending to bend it about the median surface; the moment of force in each case 30 is the tension on the respective wire times the distance k. Thus, when the temperature increases, the stress on the wire 10a, tending to bow the frame about the diagonal B'D' to a position A'B'C'D', becomes insufficient to balance the 35 sum of the stress exerted by the frame 2 and by the wire 11a tending to return the frame to the position ABCD, and the frame moves toward the latter position. When the temperature increases 40 to a value where the force on the wire 11a becomes enough greater than the force on the wire 10a to overcome the stresses in the frame, due to the warping and to the tension of the wire 10a, the frame is moved to a position past the position 45 of instability ABCD. As the frame is moved through the position ABCD, the stresses in the frame undergo a reversal in direction, and abruptly reverse the direction of curvature of the frame. A rapid movement of the frame into the position A''B''C''D'' is effected by the stresses in the 50 frame and the tension exerted by the wire 11a.

When the temperature decreases, the force exerted upon the wire 10a increases more rapidly than the force on the wire 11a, and the frame is moved back toward the position ABCD, and when 55 the temperature drops to a predetermined value, the frame is moved through the latter position and snapped to the position A'B'C'D'.

The action of the wires 10b and 11b is similar to the action of the wires 10a and 11a, but, since 60 the frame curves along the diagonal AC with a curvature opposite to the curvature along the diagonal BD, the action of the wires 10b and 11b, when the temperature increases, is reversed in direction. That is, the wire 10b expands more 65 rapidly than the wire 11b, and moves the corner portions from the positions A'C' to A''C''. When the temperature again drops, the corner portions are returned to the positions A'C'. Either the pair of wires 10a, 11a, or the pair 10b, 11b, may be 70 omitted and the thermostat will operate satisfactorily but it is preferably to employ both pairs in order to enhance the force on the frame and to prevent undesirable distortion of the frame due to unbalanced forces.

Where one or more of the wires has the same expansibility as the frame, that wire or those wires may be omitted, and the thermostat will operate with a "snap" action, but in a slightly different manner than where two wires of two different expansibilities are employed.

In this arrangement (Fig. 13), a frame 15 similar to the frame 2 may be used, and a wire 16a, or wire 16a, 16b of similar expansibilities attached 10 at opposite corners. The wires 16a, 16b may be attached in the same manner as the wires in Fig. 1, but, for the purpose of simplifying the explanation, are shown as attached to the inner margin of the frame at points 17. The description following refers to one wire 16a, but it will be understood the other (16b) acts in an analogous manner.

The position of instability or unstable equilibrium occurs when the internal stress in the frame 15, tending to move it to the position it would assume if no wire were attached, balances the tension of the wire 16a tending to pull the frame into a position of opposite curvature. The wire 16a may be assumed to exert its tension upon the frame with a moment having an arm of length g , equal to the distance of the wire from the medial plane EF passing parallel to the faces of the frame when the frame is flat.

Assuming the wire 16a to have a greater expansibility than the frame 15, upon an increase in temperature, the force moment, exerted by the wire, tending to flatten the frame 15 becomes less than the moment tending to move the frame to a position of greater curvature. As the frame moves toward a position of greater curvature, the length g becomes progressively less, and the force moment tending to move the frame into flat position becomes progressively less. Also, the internal stresses tending to curve the frame 15 increase as the frame 15 becomes increasingly curved, and hence the resultant force, tending to move the frame to a position of greater curvature, progressively increases, and an accelerating movement or "snap" action results.

Assuming the frame 15 to be in its position of greatest curvature, upon a decrease in temperature, the wire 16a contracts and moves the frame through its position of instability, whereafter the increase in the length g and decrease in internal stress in the frame produce a progressive increase of the moment tending to flatten the frame, over the moment tending to resist flattening, and the frame is snapped toward flat position.

It will be seen that, where this type of thermostat is used, it will be necessary to provide suitable stops, indicated diagrammatically at 18, to prevent the frame from moving through the flat position to a position of opposite curvature; and, in certain instances, it will also be necessary to provide stops 18 to prevent the frame from moving into a position of curvature such that the distance g becomes zero.

Since the sides of the frame (see Fig. 4) are rigid and do not bend when the frame moves from the position ABCD to the position A'B'C'D', but rock about their midpoints W, X, Y, Z, there is no change in curvature of the frame along the lines WY and XZ, and there is a maximum change in curvature along the diagonals AC and BD. The curvature along the line, such as DP, extending between a corner D and a point P, lying between an adjacent corner A and a midpoint X, is less than the curvature along the diagonal, and hence the portion of the frame along this line DP undergoes a lesser change in

curvature than along the line BD when the frame is moved between the positions ABCD and A'B'C'D'. Similarly, lines parallel to DP, as for instance RQ, undergo the same change in curvature as DP.

Thus, if wires are connected between points on the frame corresponding to the points R and Q, a small change in length thereof will produce the same movement of the frame as a greater change in length of a wire connected between B and D, as are wires 16a and 16b.

A thermostat constructed according to the present invention is well adapted for use as a component of a thermally actuated switch.

Referring to Fig. 5, the switch 20 comprises an insulating base 21 having a pair of upstanding studs 22 each carrying a blade 23 having a notch 24 for receiving outer edges of adjacent sides of a thermostat 25. A third blade 26 is secured to the base 21 by a screw 27, and has a notch 28 for engaging the inner edge of the corner of the frame 29 of the thermostat 25 between the edges engaged by the blade 23.

The thermostat 25 comprises the rectangular metal frame 29 having a cruciform central portion 30 for warping the frame 29 as above described and having portions of each side edge turned up to constitute stiffening flanges 31, the corner portions of the frame being flexible. The ends of a wire 32 are attached respectively to points on opposite sides of the frame 29, and lying on opposite sides of a line through the mid-points of the sides, a wire 33, having a similar unit length thermal expansibility, is attached between the other two sides in an analogous manner. The wires 32 and 33 are secured to the frame 29 by rotatable pins 34 with slotted heads by which the tension on the wires can be adjusted.

The corner of the frame 29 carries a contact button 35 which is positioned to move between an adjustable contact member 36, threaded into the base 21, and an adjustable contact member 37 supported from an upstanding terminal 38 secured to the base 21. Suitable conductors 39, 40 and 41 are connected to the frame 29, the contact member 36 and the terminal 38, respectively.

The thermally actuated switch 20 may be employed to control the opening and closing of an electric circuit in accordance with changes in temperature. When the device is to be used to open an electric circuit upon a predetermined change in temperature, the conductors 39 and 40 are connected to a circuit and the frame 29 or contacts 36, 37, or both adjusted to bring the contact button 35 into engagement with the contact member 36. The current flows through the frame 29 and the contact button 35 to the contact member 36. When the temperature of the atmosphere surrounding the switch increases, the wires 32, 33 and frame 29 expand at different rates, and, if the frame 29 has a greater expansibility than the wires 32 and 33, then when a predetermined temperature is attained, the frame 29 is moved in a direction to cause the contact button 35 to move rapidly out of engagement with the contact member 36 and through the position of instability, and against the contact 37. The circuit is broken when the contact button 35 is separated from the contact member 36. When the temperature again drops to the predetermined value, the frame 29 causes the contact button 35 to move back into engagement with the contact member 36, to reclose the circuit.

Although the thermal switch has been shown as employing one form of thermostat contem- 75

plated by the present invention, it will be obvious that any of the other forms of the thermostat herein disclosed may be employed in the construction of a switch of the same general form as the one disclosed.

Where it is desired to exert a stronger force upon the frame than is conveniently possible with a single pair of wires of different expansibilities, two sets of wires may be employed, each set including a plurality of wires of the same expansibility and wherein the wires of each set have different expansibilities.

Referring to Fig. 7, a frame 58 having flanges 51 formed along the sides to stiffen the sides, except at the corner portions, has attached thereto two wire screens 52 and 53 each being attached to opposite faces of the frame 58. In the screen 52, the wires 54 constituting the "warp" of the screen have similar unit length thermal expansibilities, and the wires 55 constituting the "woof" of the screen have similar expansibilities but different from that of the wires 54. In the screen 53, the "warp" 57 has the same expansibility as the "woof" 55 of screen 52, and the "woof" 56 the same as the "warp" 54.

The frame when in use is suitably compressed between one or more pairs of equal and opposite forces applied to sides to warp the frame in the manner aforementioned.

Instead of a frame, an imperforate plate may be used, as illustrated in Fig. 8. In this form an imperforate rectangular plate 60 has its edge portions stiffened, as by a flange 61 except at the corners. A plurality of wires 62-69 are connected between pairs of points, of which the points lie in opposite sides of a diagonal. The wires 62-65 have a similar unit length thermal expansibility which is different from that of the wires 66-69. Similarly the wires 70-73 and the wires 74-77 are connected to the other face of the plate. The wires 62-65 and 70-73 have the same expansibility, and the wires 66-69 and 74-77 have the same expansibility. The plate 60 is compressed between equal and opposite forces applied equally on both pairs of midpoints of the sides in a manner analogous to the forces W, X, Y and Z, indicated in Fig. 2 to warp the plate oppositely about its diagonals. When a predetermined temperature change occurs, the wires and plate change their respective dimensions at different rates, and the curvature of the plate is abruptly reversed.

In another form (Fig. 9) a strap or bar may be substituted for the wires, and may be placed under either a compressive stress or a tensile stress. A plate 80 is suitably stiffened along a portion of each edge portion by beads 81, and a bar or strap 82 having a different unit length thermal expansibility than the plate is secured to the plate 80 along a diagonal. Similarly, a second strap 83, having a similar expansibility to the first strap, may be secured to the other face along the other diagonal. The plate 80 is compressed between equal and opposite forces applied to mid-points of the sides in a manner similar to that above disclosed to warp the plate 80. At temperatures below the predetermined operating temperature, the plate is bowed about its diagonals in opposite senses. Upon the occurrence of a predetermined temperature change, the straps 83, 84 and the adjacent portion of the plate change their lengths unequally, and the plate 80 is warped in the reverse sense. A slightly different construction may employ a rod, or other stiff member may be substituted for the strap shown.

Where it is desired to produce a substantial movement of the frame by a very small elongation of the wire or wires, the center line of the wire or wires must be brought close to the median surface of the frame. In the thermostat 1 of Fig. 1, this is done by disposing the wires as close to the faces of the frame as possible, the offset in the cruciform strap serving not only as means for tensioning the arms of the strap, but also permitting the wires to be set close to the frame. 10

Where the wires are disposed in opposite faces of the flat frame, the center lines will be separated a distance equal to the thickness of the frame plus the sums of the radii of the two wires. The wires may be brought closer together by disposing them on the same side of the frame, but provision must be made so that the center-lines of the wires lie in opposite sides of the median surface of the frame in order to obtain the differential action of the wires. The differential action may be accomplished with both wires on the same side of the frame by offsetting the portion of the frame to which the ends of the wires are attached, so that the median surface passes between the axes of the wires. 25

In one form, (Fig. 10) a frame portion 90 is provided with an offset portion 91, to which a pair of wires 92 is attached at one portion, and a wire 93 is attached to another portion. The frame portion 90 is so formed and positioned with respect to the frame (not shown), that the median surface of the frame passes between the center of the wires 92 and 93. Thus, when a predetermined change of temperature occurs, the wires 92, 93 act to warp the frame (not shown), 35 in the manner described previously. Where wires are attached to the same face of a frame, and they are disposed side by side, as shown, it is preferable to provide two wires 92 having the same unit length thermal expansibility and a 40 third wire 93 having a different expansibility disposed between the two wires 92. Thus, the forces tending to impart undesirable distortion to the frame are balanced.

Another mode (Fig. 11) of attaching the wires 45 consists in forming a frame 100 with a flat offset portion 101 to which the wires are attached. A pair of similar wires 102 are attached to the offset portion 101 and a wire 103 having a different expansibility and a greater diameter is attached 50 to the frame 100 between the wires 102. The offset portion 101 of the frame 100 is sufficiently offset, and the relative diameters of the wires 102 and 103 so selected, that the median surface of the frame 100 passes between the plane of the 55 axes of the wires 102 and the axis of the wire 103.

As stated in the foregoing, the end of the wires may be attached by various means such as by the pins shown in connection with the thermal switch, by rivets or eyelets, by soldering or brazing, or by other means.

Where the ends of the wires are attached by soldering or brazing, it is often desirable to provide means for adjusting the tension on the wires. This may be done by constructing a frame 65 110 (Fig. 12) having an ear 111 to which a wire 112 is soldered. The tension on the wire may be adjusted by bending the ear 111 toward or away from the plane of the frame 110.

Instead of the wire or wires being connected 70 at both ends to the frame, one end only may be connected to a suitable point on the frame, and the other end connected to some point on a member other than the frame; the frame and member will, of course, be suitably mounted and the fixed 75

point so positioned relative to the frame that the tension on the wire is in the proper direction to effect a movement of the frame upon a predetermined temperature change.

5 The principle of a warped frame moved between two positions of stability by a control member, which changes its length in accordance with a change in the condition of the medium surrounding the control member, is capable of wide application.

10 A device constructed according to the principles of the present invention may be employed to indicate the presence of certain gases, or to operate other mechanisms when such gases surround it.

15 A frame and wire structure, constructed according to the principles above-disclosed, is provided with a wire or wires having a coating of spongy platinum, or the like, which becomes heated in the presence of certain gases.

20 When the gas or gases surround the wire or wires in sufficient concentration, the wire is heated and effects movement of the frame to indicate the presence of the gases, or operate the associated mechanism.

25 The invention also contemplates use of the principle of the warped sheet and expandable member in the construction of hygrostats. A hygrostat may be constructed in a manner

30 analogous to the thermostat by substituting hygroscopic members, such as catgut filaments, for effecting a movement of the frame upon a predetermined change in the relative humidity of the atmosphere surrounding the hygrostat.

35 As will be understood, a change in the moisture content of the filaments changes their lengths, and thereby changes the pull exerted on the frame to move the latter. Thus, the movement of the frame may be utilized to indicate a predetermined change in relative humidity, or to operate associated apparatus.

40 The present invention provides a movement-producing device wherein an element is moved in accordance with a change in the length of an attached control element induced by a change in temperature, gaseous composition, relative humidity or other changes in the condition of the medium surrounding the control element.

45 In such a device a very small change in length of the control element effects a correspondingly greater movement of the other element. The control element, being in most cases very small in volume, responds quickly to change its length when the predetermined stimulus occurs. This is especially true in the case of the thermostat, inasmuch as the wire is of small cross-section, 50 and is in contact with the frame over a small distance, and it is therefore quickly heated or cooled in accordance with a change in temperature.

55 The device, in most of its forms, inherently provides a "snap-action" which is desirable in many instances such as where it is desired to indicate that the device has operated or where a rapid movement of the frame into the final position is desired, or the like.

60 One advantage possessed by a device constructed according to the present invention is that each of the various elements of the device is relatively complete within itself, and hence each 55 element may be bent, drawn, formed, heat-treated or otherwise operated upon separately prior to attachment to the other elements. Thus, one element may be given a treatment which might adversely affect the other elements were they so

65 formed and joined that the treatment could

only be carried out upon all of the elements simultaneously.

Other advantages possessed by the device are that it is simple and inexpensive to construct, rugged and reliable in operation, and lends itself to a large number of modifications and adaptations.

It will be understood that while the various forms of the invention have principally been illustrated as using wires of small cross-section and capable of exerting a tension only, the wires may be replaced by rods capable of exerting either a push or a pull upon the associated member or members.

It is also to be understood that where the term "diagonal" is used it is not to be limited to mean a line joining two corners of a geometrical figure, but is to be understood as designating a line which is non-parallel with respect to the sides of a figure, or more particularly, non-parallel to the rigid portions of a frame or sheet element.

While certain novel features of the invention have been disclosed and are pointed out in the annexed claims, it will be understood that various omissions, substitutions and changes may be made by those skilled in the art without departing from the spirit of the invention.

What is claimed is:

1. A resilient flexible element rigid along discontinuous portions and initially stressed to curve it oppositely about lines extending between non-adjacent flexible portions, and a second element secured to said first element at portions lying on opposite sides of one of the lines about which said first element is curved, said second element being responsive to a predetermined change in temperature to change its length, and effect an abrupt change of curvature of said first element.

2. A resilient frame initially stressed to warp it oppositely about two intersecting lines extending along the surface between points on the periphery thereof, and a second element connected between portions of the periphery lying on opposite sides of one of the lines of curvature and responsive to a change in length to reverse the direction of the moments of the initial stresses in said first element to thereby produce an abrupt reversal of curvature of said first element.

3. In combination, a resilient element flexible along its diagonals and having rigid portions extending between the diagonals, means for warping said element in opposite senses about its respective diagonals, a second element having a different thermal expansibility than said first element, and attached to said first element at portions on opposite sides of a diagonal, said second element being responsive to a predetermined change in temperature to effect a change of curvature of said first element about its diagonals.

4. In combination, a resilient element having spaced rigid portions, and stressed to flex it about its diagonals, and a second element connected between spaced portions of said first element on opposite sides of a diagonal, said second element having a thermal expansibility such that, upon a predetermined temperature change, said first element is moved through a position of unstable equilibrium to a position of flexure different from the flexure of its initial position.

5. A device for producing a snap-action movement upon a change in the condition of the medium surrounding the device, comprising an element having flexible diagonal portions, and rigid portions extending between the diagonal portions, said element being initially stressed to warp it

oppositely about the flexible diagonal portions, and a second element, said elements being relatively expansible in response to a predetermined change in the condition of the surrounding medium, and means attaching said second element to said first element at points on opposite sides of a diagonal thereof, said elements being active upon a predetermined relative change in dimensions to effect an abrupt change of curvature of said first element.

10. A thermostat comprising a resilient element having rigid side portions and flexible along its diagonals and curved about its diagonals in opposite senses, a second and thermally expansible element, and means connecting said expansible element to said resilient element for effecting an abrupt change of curvature of said first element upon a thermally-induced predetermined change in the length of said expansible element.

15. A thermostat comprising a resilient element having spaced, stiffened side portions and stressed to curve it concavely about one diagonal and convexly about the other diagonal, a plurality of elongate elements having different thermal expansibilities respectively, and means connecting each of said elongate elements to portions of said resilient element on opposite sides of a diagonal, said elongate elements being of such expansibility relative to each other and to the resilient element as to produce an abrupt change of curvature of said resilient element upon a predetermined temperature change.

20. A thermostat comprising an element having two pairs of oppositely disposed rigid portions and flexible portions therebetween, means stressing said element to curve it oppositely along lines extending between said flexible portions, a second element having a unit length thermal expansibility different than that of the first element, and means attaching said second element to portions of said first element lying on opposite sides of one of said lines of curvature, said second element being stressed to effect an abrupt change of curvature of said first element when a predetermined change in temperature effects a predetermined change in the relative stresses on said elements.

25. A thermostat comprising a plate-like member having at least two angularly disposed rigid portions and flexible portions intermediate said rigid portions, means for initially stressing said element to warp it about lines extending between the flexible portions, and a plurality of members secured between portions of said first member lying on opposite sides of one of said lines of curvature, said second-named members being stressed whereby, upon a predetermined change in temperature, they alter the angularity of said rigid portions to effect an abrupt change of curvature of said plate-like member about the lines of curvature.

30. A thermostat comprising a plate-like element of flexible material, means stiffening spaced portions of said element against bending, means warping said element about lines extending between opposite non-stiffened portions and a second element secured continuously to said first element and extending between portions of the first element lying on opposite sides of one of said lines of curvature, said second element being active upon a predetermined temperature change to move the first-named element through a position of instability to a position of different curvature from the initial position.

35. A thermally actuated snap switch, comprising an element having relatively rigid por-

tions relatively movable to varying positions of angularity, means establishing a toggle action of said relatively movable portions, a contact carried by a movable portion of said element, and a second and homogeneously thermally expansible element connected to at least one of said movable portions, and active upon a thermally induced change in the relative dimensions of said elements to effect a snap-acting actuation of said contact-carrying portion, and means for passing an electric current through at least one of said thermostatic elements.

40. A thermostat comprising an originally planar element having alternate rigid and flexible peripheral portions, means urging at least two of said rigid portions toward one another to warp said element about intersecting lines of curvature, and means for abruptly reversing the direction of curvature of said element upon a predetermined change in temperature including a pair of elongate elements having non-similar thermal expansibilities, each of said elements being secured at its ends to portions of said first-named elements on opposite sides of one of said lines of curvature, the axes of said elongate members being spaced from a medial surface passing parallel to the faces of the first-named element, whereby the differential forces applied to said first-named element by said elongate members upon a change in temperature bend said first-named element about said lines of curvature.

45. In combination, a thin rectilinear frame member formed of flexible resilient material stiffened along discontinuous portions to provide rigid side portions and flexible corner portions, means stressing said member to curve it in the opposite senses along its diagonals, an elongate member connected at its end to portions on one face of the rectilinear member lying on opposite sides of a diagonal thereof, a second elongate member connected at its ends to the other face of said rectilinear member, the thermal expansibilities of said elongate members, relative to said frame member, being such that, upon a predetermined change in temperature, said elongate members exert a stress upon said rectilinear member to change the curvature thereof about its diagonals.

50. A snap-acting device comprising a resilient snap-acting frame initially stressed to warp it about intersecting lines extending along the surface defined by the frame element, and an element connected between portions of said frame lying on opposite sides of at least one of said lines of curvature, said frame and connected element being responsive to a relative change in their dimensions to effect an abrupt change of curvature of said frame.

55. A snap-acting element comprising a frame having relatively rigid rectilinear portions connected by relatively flexible, resilient connecting portions, and means stressing said frame to warp it into a position wherein said rigid portions lie substantially in a hyperbolic paraboloidal surface, whereby said frame has at least one position of stability to which the frame tends to return if warped therefrom.

60. In a measuring instrument, a first member of substantially homogeneous material, a second member of material substantially homogeneous but dissimilar to the material forming said first member, said second member being secured to said first member at spaced points and unsecured between said points, the stresses on

said members being so arranged that said first member, upon relative change in length through a given value, will snap from one position to another.

5 17. In a snap-acting device, in combination, a first element having at least a portion thereof relatively rigid, means mounting said first element for movement of at least the rigid portion, means establishing a toggle-acting movement of said rigid portion, and a second element attached between spaced and relatively movable portions of said first element and active upon a predetermined change in the relative dimensions of said members to effect a snap movement of said rigid portion.

10 18. In a measuring instrument, a rectangular frame having relatively stiff sides articulately connected at the corners thereof, a force-applying member for applying a force to opposite sides of said frame to distort said frame, and an active temperature-responsive element secured between relatively movable portions of said frame.

15 19. In a measuring instrument, a quadrilateral frame having comparatively stiff sides articulately connected at the corners of the frame, and a transverse strap connecting at least two sides of said frame, the tension of said strap being increased when said frame is moved from a limiting position.

20 20. In a movement-producing device, in combination, a first element, means establishing a displacement stress characteristic of said first element varying from zero internal displacing stress and maximum normal displacement through maximum internal displacing stress to zero internal displacing stress and zero displacement, and a second element attached to at least one movable portion of said first element and exerting a stress moment upon said first element, which is zero at the displacement corre-

sponding to the maximum displacing stress of said first element, and which varies with the displacement of the point of attachment between said elements and the effective relative dimensions of said elements, whereby, upon a predetermined change in relative dimension of said elements, said first element is moved through a position of unstable equilibrium, and into a position of relative stability, with a snap-action.

5 21. A movement-producing device comprising an initially planar element having relatively rigid peripheral portions, with relatively flexible portions therebetween, means subjecting said element to forces tending to urge opposite of said rigid portions towards one another, whereby said element tends to warp out of flatness into conformation with a substantially hyperbolic paraboloidal surface.

10 22. A measuring instrument including a frame having quadrilaterally arranged, relatively rigid portions, connecting portions joining the ends of adjacent of said rigid portions and permitting relative movement of said rigid portions, a flexible portion connecting opposite of said rigid portions intermediate the ends thereof, said rigid portions and said flexible portions together approximately defining a surface, and means stressing said flexible portions whereby to cause said frame to warp oppositely about intersecting lines on said surface.

15 23. A measuring instrument including a frame having quadrilaterally arranged, relatively rigid sides, relatively flexible corner portions connecting the ends of adjacent sides, a cruciform strap portion having each of its intersecting arms extending between points intermediate the ends of opposite sides of the frame, and means stressing said strap whereby to cause said frame to assume an anticlastic form.
